UNITED STATES PATENT OFFICE.

LOUIS N. LUMB, OF ASTORIA, NEW YORK.

BED LOCK.

Application filed July 30, 1925. Serial No. 46,944.

This invention is a bed lock adapted for use on metal bedsteads which, as a general rule, embody a head board and a foot board connected by side rails of angle cross section. 5 Both the head and foot boards embody upright posts and to these posts the opposite ends of the side rails are connected by suitable demountable attaching means, known to the trade as "locks". The bed posts are 10 made hollow and of metal and permanently secured thereto are attaching members with which engage cooperating attaching members mounted on the opposite ends of the side rails.

15 The object of the present invention is to provide a simple and convenient bed lock which will secure the side rails to the bed post in a perfectly rigid manner and in such way as to preclude their inadvertent disengagement, but to permit of the manual assembling or dismantling of the bed without the employment of tools or without the exercise of any mechanical skill or ingenuity. In other words, it is the object of this invention 20 to provide a novel and efficient bed lock which even the most uninitiated can readily assemble and dismantle.

A further object of the invention is to provide a bed lock so constructed that side 25 rails may be associated with the corner posts in a manner to adapt said rails to support either the common flat spring or a spring of conventional "box" type.

With these considerations in mind, the invention in its preferred practical form embodies a wedge member adapted to be secured in a permanent manner to a corner post and constituting in part an upstanding wedge. The other element of the lock is in 30 the form of a plate suitably embossed to provide two abutments spaced apart with respect to one another and at least one of which abutments is shaped to provide a tapered opening between them. Said plate is adapted to be riveted to the side rail of 35 the bed and when thus secured in position, the rail may be brought into a position to cause the abutments to engage with the tapering surfaces of the wedge of the other member of the construction, the parts being proportioned, so that as the weight on the 40 side rail is increased the locking action between the parts is likewise increased, so that instead of tending to effect inadvertent release of the parts, the imposing of weight

thereon serves, on the contrary, to tighten the engagement between them.

The attaching plate which is secured to the side rail as described forms a salient feature of this invention. It is of pronouncedly 60 novel construction and is formed by offsetting the plate and embossing it in such manner as to produce the abutments to which I have referred.

The embossing operation is in practice 65 carried out by a die and the shaping of the plate may be accomplished in one operation, thereby minimizing the manufacturing costs without sacrifice to strength or appearance. The whole construction can be readily fabricated from heavy gage metal in an entirely 70 automatic and economical manner.

Features of the invention, other than those adverted to, will be apparent from the hereinafter detailed description and claims, when 75 read in conjunction with the accompanying drawings.

The accompanying drawing illustrates one practical embodiment of the invention, but the construction therein shown is to be understood as illustrative, only, and not as defining the limits of the invention.

Figure 1 is a side elevation of the bed lock embodying the present invention.

Figure 2 is a plan view of the construction 85 shown in Figure 1.

Figure 3 is a section on the line 3—3 of Figure 1.

Figure 4 is a horizontal section through the center of the attaching member which is associated with the side rail of the bed and this member is shown in Figure 4 as removed from the side rail and in section on the line 4—4 of Figure 1.

Figure 5 is a section on the line 5—5 of 95 Figures 1 and 4; and,

Figure 6 is a section on the line 6—6 of Figures 2 and 4.

Referring to the drawings, 1 designates one of the posts of a bed and 2 one of the 100 side rails. The lock of this invention, as shown in the drawings, embodies an attaching member 3 provided at its base with a flange 4 adapted to conform to the cross sectional shape of the post 1 and secured thereto by bolts or rivets 5, as shown in Figures 1 and 2. The bolts or rivets 5, preferably pass through a back plate 6 positioned interiorly of the post 1, so as to furnish rigid attachment of the flange 4 to said post. From one 105 110

vertical edge of the flange 4, the attaching member 3 extends in a direction parallel to the side rail of the bed in the form of a relatively thin plate with the free end of which is integrally formed an upstanding wedge 7, which tapers upwardly, as shown best in Figure 1.

Secured to the side rail 2 by means of rivets 8 and 9 is a cooperating attaching member 10 which forms an important part of this invention. This attaching member is in the form of a plate which is offset, as shown at 11, to form the body of the plate in two distinct planes. That is to say, the portion 12 of the plate is adapted to lie over against one flange of the side rail, while the remaining portion 13 is spaced a distance from the side rail substantially equal to the thickness of the wedge 7 and extends substantially parallel to said side rail. This portion 13 may therefore be referred to as the overlying portion of the plate inasmuch as it overlies the wedge 7, as clearly appears from Figure 2. Stamped inwardly adjacent the free end of the portion 13 of the plate is a boss 14, one face 15 of which constitutes an abutment. To produce this boss, the plate is embossed or stamped inwardly for a distance sufficient to cause it to engage with the face of the side rail, and said boss is perforated at 16, so that the rivets 8 can be passed through the perforations thus formed and headed over to tightly bind the boss to the side rail.

In the operation of offsetting the plate at 11 as described, a die is used which will so emboss the plate as to form on the inner face of the plate and at the offset an abutment 17. This abutment is preferably shaped, as shown in Figure 1, to embody two parts 17^a and 17^b, which are out of alignment and form with one another an angle of greater than 180 degrees, so that the space between the two parts of the abutment 17 and the abutment 15 converges toward the center line of the side rail 2, as is clearly apparent from Figure 1. By this arrangement, the side rail may be brought either into the position shown in Figure 1, wherein the wedge 7 will cooperate in the wedging engagement with the abutment 15 and the abutment portion 17^b, or said rail may be reversed or inverted, so that the abutment portion 17^a of the lock at the other end of the side rail will cooperate with the abutment 15 to receive and grip the wedge. In either case a tight wedging engagement of the parts will result and a rigid bed assembly is obtained.

Attention is directed to the fact that the rivets 8 and 9 extend through the parts which form the abutments and inasmuch as it is these portions of the construction which directly carry the strain, it becomes apparent that the strain is borne by the strongest parts of the construction. That portion of

the plate 10 which extends between the abutments serves to tie the abutments together and eliminates any bending stresses to which the rivets might otherwise be subjected.

The foregoing detailed description and the drawing deal with the invention in its preferred practical form. I am aware, however, that slight modifications in the illustrative showing may be made without departing from the spirit of this invention; that is to say, the bed post 1 may be made of other shapes than cylindrical and the cross angle support 18, while shown as secured in place by the lower rivet 5 may be otherwise held in position. Furthermore, the plate 10 is shown as flared outwardly at 19 to permit the wedge to be guided into engagement with the abutments 15 and 17 (see Fig. 6), but this flaring may be omitted if desired. For these reasons, the present invention is to be understood as fully commensurate with the appended claims.

Having thus fully described the invention, what I claim as new and desire to secure by Letters Patent is:

1. In a bed lock, the combination with a corner post and a side rail, of a wedge member permanently secured to the corner post and embodying an upstanding wedge, and an attaching plate permanently secured to the side rail and embossed to provide spaced apart abutments forming between them a constriction tapering both upwardly and downwardly to permit tight engagement of the wedge with said abutments when engaged thereby in either direction, and rivets passing through the embossed portions of the plate and through the side rail to secure said plate to the rail.

2. In a bed lock, the combination with a corner post and a side rail, of an attaching member mounted on the corner post and embodying an upstanding wedge, an attaching plate permanently secured to the side rail and having spaced embossed portions forming spaced abutments at least one of which is shaped to form, with the other, a constriction tapering both upwardly and downwardly to permit tight engagement of the wedge with said abutments, when engaged thereby in either direction, and rivets passed directly through the embossed portions of the plate and through the side rail for rigidly securing said embossed portions directly to the rail.

3. In a bed lock, the combination with a corner post and a side rail, of an attaching member mounted on the corner post and embodying an upstanding wedge, an attaching plate extending longitudinally of the side rail and having longitudinally spaced embossed portions stamped laterally from the body of the plate, intermediate its upper and lower edges, and forming spaced abutments to collectively constitute a tapering

constriction with which the wedge may co-operate to form a tight fit, and rivets passed directly through the embossed portions in close proximity to the abutments and 5 through the side rail, for rigidly securing the embossed portions tightly to the rail.

4. In a bed lock, the combination with a corner post and a side rail, of an attaching member mounted on the corner post and 10 embodying an upstanding wedge, an attaching plate extending longitudinally of the side rail and having longitudinally spaced embossed portions stamped laterally from the body of the plate, intermediate its up-

per and lower edges, and forming spaced 15 abutments to collectively constitute a constriction tapering both upwardly and downwardly to permit tight engagement of the wedge with said abutments when engaged thereby in either direction, and rivets passed 20 directly through the embossed portions in close proximity to the abutments and through the side rail, for rigidly securing the embossed portions tightly to the rail.

In testimony whereof I have signed the 25 foregoing specification.

LOUIS N. LUMB.
